US00D636533S

(12) **United States Design Patent**
Andersen et al.

(10) **Patent No.:** **US D636,533 S**
(45) **Date of Patent:** **** Apr. 19, 2011**

(54) **RAZOR HANDLE**

(75) Inventors: **Michael L. Andersen**, Montclair, NJ (US); **David C. Stowers**, Morristown, NJ (US)

(73) Assignee: **American Safety Razor**, Verona, VA (US)

(**) Term: **14 Years**

(21) Appl. No.: **29/361,452**

(22) Filed: **May 11, 2010**

(51) **LOC (9) CL. 28-03**

(52) **U.S. CL. D28/48**

(58) **Field of Classification Search** D28/44-48; 30/32, 32.05, 34.1-34.2, 41, 44-46, 47-51, 30/57-58, 77-84, 526-539

See application file for complete search history.

(74) *Attorney, Agent, or Firm* — McDermott Will & Emery LLP

(57) **CLAIM**

The ornamental design for a razor handle, as shown and described.

DESCRIPTION

FIG. 1 is a top perspective view of the razor handle, showing the new design;

FIG. 2 is a top view of the razor handle;

FIG. 3 is a bottom view of the razor handle;

FIG. 4 is a side view of the razor handle;

FIG. 5 is another side view of the razor handle;

FIG. 6 is a front view of the razor handle; and,

FIG. 7 is a rear view of the razor handle.

1 Claim, 4 Drawing Sheets
